UNITED STATES PATENT OFFICE

122,315

DESIGN FOR A CONTAINER FOR POWDERED SOLIDS

Preston B. Heller, Chicago, Ill.

Application December 16, 1938, Serial No. 81,817

Term of patent 14 years

To all whom it may concern:

Be it known that I, Preston B. Heller, a citizen of the United States, residing at Chicago, in the county of Cook and State of Illinois, have invented a new, original, and ornamental Design for a Container for Powdered Solids, reference being had to the accompanying drawing, forming a part thereof.

In the drawing:

Fig. 1 is a perspective view of the container showing my new design; and

Fig. 2 is a top plan view thereof.

The design is characterized by a container of the configuration disclosed having on the top thereof a raised portion of the form illustrated and spaced from the upper walls of the container in the manner shown, said raised portion being provided with a centrally disposed series of indentations as illustrated.

I claim:

The ornamental design for a container for powdered solids, as shown and described.

PRESTON B. HELLER.
